UNITED STATES PATENT OFFICE.

JAMES BORLAND, OF XENIA, OHIO.

CUSHION.

1,372,270.

Specification of Letters Patent. Patented Mar. 22, 1921.

Application filed November 12, 1919. Serial No. 337,452.

To all whom it may concern:

Be it known that I, JAMES BORLAND, a citizen of the United States, residing at Xenia, in the county of Greene and State of Ohio, have invented certain new and useful Improvements in Cushions, of which the following is a specification.

My invention relates to seat cushions, and more particularly to a temporary cushion 10 for use on amphitheater seats such as circus seats, seats in the viewing stand at race tracks, ball games, Chautauqua meetings, or excursion steamers, but also suitable for use as temporary cushions on porches or for 15 picnic purposes.

The object of the invention is to provide a cheap, simple, and sanitary cushion, which will be of light weight, economical to manufacture and so inexpensive that when used 20 or soiled, it may be discarded or destroyed.

A further object of the invention is to provide a casing or container foldable to compact form, and of light weight, which will enable a great number to be carried or 25 transported from place to place with little effort or inconvenience.

With the above primary and other incidental objects in view as will more fully appear in the specification, the invention 30 consists of the features of construction, the parts and combinations thereof, and the mode of operation or their equivalents as hereinafter described and set forth in the claims.

35 Referring to the drawings, Figure 1 is a perspective view of the seat cushion or pad forming the subject matter hereof. Fig. 2 is a transverse sectional view thereof substantially on line 2—2 of Fig. 3. Fig. 3 is 40 a perspective view of an envelop or casing viewed from the under or bottom side, the casing being opened and partly torn away to disclose the details of construction. Fig. 4 is a modification.

45 Like parts are indicated by similar characters of reference throughout the several views.

The cushion or seat pad forming the subject matter hereof is designed to be sold by 50 concessionaries or "privileged men" at circuses, racing meets, county fairs, ball games, excursion steamers, and like places. During recent years there has developed a considerable business in renting cushions or seat pads 55 for amphitheater seats, reviewing stands,

and places where unupholstered benches or board seats are provided. These cushions or seat pads, however, are of a more or less bulky and expensive type. Such cushions or seat pads are not sold outright, but are 60 merely rented for the occasion and through repeated and continuous use become very unsanitary. Furthermore, such cushions and seat pads are the occasion of much dissension and conflict between the concessionary 65 or privileged man and his customer who refuses to surrender the cushion or pad when he has finished his use of it, but insists upon carrying it away with him. The losses from this source are quite considerable and the 70 arguments and discussions occasioned quite disagreeable.

The present invention is designed to provide a cushion or seat pad of temporary character at a cost sufficiently small that 75 after being once used it may be discarded. In any event it will not be of sufficient monetary value to encourage the user to carry it away with him. Furthermore, being of such character that it is not capable of 80 withstanding the use of more than a few occasions, it necessitates frequent replacement, and hence is much more sanitary than a continuously used cushion or pad of higher quality and more expensive manufacture. 85

The cushion or seat pad comprises a paper envelop having a cover section extending beyond the margin of the envelop to which it is attached. In the drawings the cover section 1 is shown provided with an 90 ornamental border or design which will render it effective and pleasing in appearance. On the under side of this cover section 1 is provided a pocket 2 of less dimensions than the cover section to which the 95 cover section 1 forms an inclosure or envelop for a filling 3 which may be of straw, excelsior, dried grass or other suitable material. For convenience of manufacture the pocket 2 is preferably formed from a sheet 100 of paper or light material three marginal edges of which have been folded inward as at 4—4 and 5. As shown in the drawings the lateral margin 4 has been folded over the bottom margin 5. These inwardly folded margins 4 and 5 are attached to the upper side of the cover section 1 by gluing, pasting or cementing the folded margins to the cover section adjacent to their edges as shown in Fig. 2. By this arrangement 110

cover section 1 forms one side of the pocket or casing and so economizes materials. A triangular flap or closure 6 is secured to the under side of the cover section 1 by pasting, 5 gluing or cementing one of the marginal edges thereto with the extreme ends of the flap extending either under or over the in-folded margins 4. This closure flap 6 is adapted to be secured in its closed position 10 as indicated by dotted lines in Fig. 3 by any suitable form of clasp or fastening means. In the drawing there has been shown an ordinary form of paper fastener 7 which is adapted to be projected through the eye 8 15 of the flap 6, and the end of the fastener 7 bent outward.

While the construction above described is to be preferred on account of the economy of materials it is obvious that in lieu of 20 making the cover section 1 a part of the pocket or casing that an ordinary paper envelop of sufficient size may be employed to which the cover section 1 is secured. Such a construction is shown in Fig. 4, in which 25 9 is an ordinary envelop of large size and 1 the cover section secured thereto. In Fig. 4 the pad or seat has been shown empty and in inverted position.

In any event, however, it is to be noted 30 that the lines of attachment of the cover section 1 are inside the margin of the pocket or envelop section, that is to say the envelop casing is free about its marginal edges from the cover section 1, as shown at 10 in Fig. 35 2, and that furthermore the cover section 1 is of materially larger dimensions than the casing or envelop whereby it projects beyond the margins of the casing or envelop thus comprising loose marginal flaps.

40 The construction as shown and described affords a cheap light and compact casing which may be packed in great numbers in a comparatively small case or packing box for transportation. The device is such that 45 the concessionary or "privileged man" may pack several hundred of these containers in an ordinary suit case and upon reaching the fair grounds or circus lot he may purchase a bail of straw or excelsior and proceed to 50 fill the cushion or pad as needed. The cushions being of such character that they are not likely to be carried away by the users or if carried away the monetary loss is comparatively small, the concessionary or 55 "privileged man" may go through the reviewing stand or seats and salvage such cushions or pads as may be capable of further use. However, in any event the life of the cushions or pad will be quite short and its use 60 will be limited to a very few occasions. Consequently there is but little opportunity for the cushions to become unsanitary as is the case with more valuable cushions which are used for long periods of time.

65 While the cover section 1 has been shown

in the drawing as provided with an ornamental border or design, this cushion will afford a very desirable form of advertising which may be placed upon the cover section 1. The loose marginal flaps 11 of the cover 70 section materially improve the appearance of the cushion or pad and if made of sufficient length or extent beyond the margin of the casing or container they will turn down over the edges of the seat and so protect the 75 clothing of the user. In the event that the seats are provided with backs the rear margin of the cover section 1 may be turned upward against the back for the same purpose. While for convenience of illustration the 80 loose marginal edges of the cover section 1 has been shown comparatively short in the drawings it is to be understood that these loose marginal flaps may be projected to any desired extent beyond the margins of 85 the container or casing 2.

From the above description it will be apparent that there is thus provided a device of the character described possessing the particular features of advantage before 90 enumerated as desirable, but which obviously is susceptible of modification in its form, proportions, detail construction and arrangement of parts without departing from the principle involved or sacrificing 95 any of its advantages.

While in order to comply with the statute the invention has been described in language more or less specific as to structural features, 100 it is to be understood that the invention is not limited to the specific details shown, but that the means and construction herein disclosed comprise but one of several modes of putting the invention into effect, and the invention is therefore claimed in any of its 105 forms or modifications within the legitimate and valid scope of the appended claims.

Having thus described my invention, I claim:

1. As an article of manufacture, a paper 110 cushion for amphitheater seats and the like, comprising a paper envelop for a body of filling material, said envelop forming a complete inclosure including a cover sheet of larger dimensions than the pocket for filling 115 material, the juncture lines of the cover and filling material pocket being spaced inward from the edge of the pocket.

2. As an article of manufacture, a paper 120 cushion for amphitheater seats and the like, comprising a face or cover section and a pocket to contain filling material secured to the under or reverse side of said cover section, said pocket being of less extent than the cover section and forming a complete inclosure for a body of filling material, the juncture line of the cover section and pocket being spaced inward from the edges of the pocket beyond which edges the cover section 125 extends.

3. As an article of manufacture, a paper cushion for amphitheater seats and the like, comprising a pocket forming a complete enclosure for a body of filling material, said
5 envelop having loose marginal flaps attached to the pocket on juncture lines in spaced relation from the margins of the pocket and projections beyond said margins.

In testimony whereof, I have hereunto set
my hand this 1st day of November A. D. 10
1919.

JAMES BORLAND.
